ELMER E. NEAL, OF NEW HAVEN, CONNECTICUT, ASSIGNOR TO PEERLESS HANDCUFF COMPANY, OF SPRINGFIELD, MASSACHUSETTS, A CORPORATION OF MASSACHUSETTS

LOCK MECHANISM

Application filed October 24, 1929. Serial No. 402,189.

This invention relates to an improved lock mechanism constructed particularly for use in officer's irons, such as handcuffs, thumbcuffs, leg irons, and like devices for restricting a prisoner's movements. It will be described in its preferred form as a handcuff mechanism, and its other uses will be apparent from this description.

The features of the invention will be made clear as its preferred form is described in detail and then they will be pointed out in the annexed claims.

In the drawings—

Fig. 1 shows one of a pair of handcuffs with the side plate of the lock casing cut away and with all the parts of the mechanism in operative position;

Fig. 1a is a detail view of the corresponding parts of Fig. 1 but with the key in the lock and holding the latch in unlocked position;

Fig. 2 is a detail view of the spring bolt or latch with its spring;

Fig. 3 is a detail view of the bolt for double locking;

Fig. 4 is a detail view of the filler piece for the lock casing which makes up the end, top, and bottom walls of such casing; and

Fig. 5 shows one form of key that may be used.

It will be understood that in the form shown, the arm 5 is pivoted at 3 to spaced arms 1 and 2 between which the filler piece 4 is fastened to make up the lock bearing arms.

In the normal operation, arm 5 may rotate completely on pivot 3, so as to pass between arms 1 and 2 in one direction. But rotation in the opposite directions is stopped by a ratchet device in the lock mechanism. So if a wrist is embraced to stop rotation in one direction, the ratchet stops it in the other, and the bracelet is locked on the wrist. This general operation is now well known.

According to one feature of my present invention I provide a novel locking means for the handcuff which has the advantage of extreme simplicity and in addition the capacity for efficient operation in the ways I will describe.

In constructing the cuff, I place the filler

piece 4 with the parts assembled with it, as shown in Fig. 1, on one of the side plates and rivet the other side plate, for example as at the points indicated, by rivet pins. Then I rivet arm 5 at pivotal point 3 for rotary movement.

The ratchet teeth 6 (on an arc from point 3) are in rotation line with the latch teeth 7. In the ratchet action the latch 8 moves straight up and down, being guided by the casing walls and filler piece 4, and is returned by its spring 9.

When the teeth are in full engagement, the bolt pusher 10 can be pressed by the end of the key or a device like a match to throw bolt 11 under latch 8 and double-lock the device against all movement between arms on pivot 3. This is the final locked position for the prisoner. The latch locks automatically in the first place and the bolt 11, operable in only one direction from without any necessary use of the key, gives the final locking movement. To unlock the cuff the key is inserted and turned to move the bolt 11 back, which resets pusher 10. Then a continued turning of the key engages lug 12 to push it down against its spring. This lug 12 is preferably formed with a cam end to hold the key in position by spring action if left in completely unlocked position. In such position the key holds latch 8 down and arm 5 can move freely in either direction. A backward movement of arm 5 unlocks the wrist. It is quite obvious that the pusher pin 10 may be an integral extension of bolt 11, if desired, as these two parts always work together with no necessary separation.

There is considerable advantage, particularly in handcuff mechanism, to have available for use when needed a variety of novel lock mechanisms. That is to say, from the policeman's or manufacturer's standpoint it may be that one mechanism will become so well known (on account of the tendency to standardize parts) that there is more danger of its being picked by the skilled criminal. Therefore, the potentiality of a desired and easy change of mechanism is considered, and in one aspect this is a purpose of my present invention as contrasted with previous ones.

To put it another way, the novelty per se has utility in these mechanisms apart from any academic view as to whether one mechanism is an improvement on another.

5 According to one feature of novelty, the key unlocks both the bolt and pawl by moving the key in the same direction, rather than by movements in opposite directions, as in one of my prior mechanisms. In addition, 10 the movement of the latch in unlocking is a straight line rather than a pivotal movement.

The new lock mechanism may be readily inserted in the lock casings of prior handcuff 15 constructions such, for example, as that shown in Fig. 3 of my Patent No. 1,531,451 of March 31, 1925. It would only be necessary in such a substitution to provide guiding means for latch 8 and bolt 11 in the lock casing of the 20 former handcuff. This could easily be done, for example, by inserting cross pins between the side plates of that lock casing to restrict latch 8 and bolt 11 to the desired straight line movements.

25 As previously mentioned, the lock mechanism of Fig. 1 has the merit of extreme simplicity. The only necessary parts aside from the lock casing and arms, are latch 8, spring 9, bolt 11, and the key. No skilled work is 30 required in fitting the lock mechanism or in originally constructing its parts. All its merit as an arresting iron of the simplest character is due to its design. It makes an effective tool for the officer's use and there 35 is nothing in it to get out of order. The key hole and key are shown as of the simplest possible form but it should be understood that these can be made in various other known forms which require only well known changes 40 of design to vary such parts for the general lock making purposes.

Having described my invention, what I claim is:

45 1. A lock mechanism for police officer's use, comprising pivoted locking arms provided with a lock casing, means in the lock casing for preventing relative rotation of the arms either in one direction or both directions, said means including as its essential parts a 50 spring pressed latch mounted for straight line movement into and out of ratchet engagement with one of said arms, a bolt slidable to and from position to block said latch against movement, said bolt arranged for movement to its blocking position by means acting from without the casing independently of the key hole in the casing and for movement from its blocking position only by a key.

55 2. A lock mechanism to restrain a prisoner's limb movements comprising rotatable locking arms and a lock casing carried thereby, a spring latch and a bolt in the lock casing, one of said arms having teeth for latch engagement, said latch and bolt each 60 arranged for a straight line movement one

at an angle to the other whereby the bolt may be moved to block all movement of the latch when the latter is in engagement with said teeth.

3. A lock mechanism to restrain a prisoner's limb movements, including a lock casing, a bolt slidable on the bottom of said casing, a spring latch slidable in a straight line against a side wall of said casing at an angle to the bolt, a small opening in the opposite side wall of the casing whereby the bolt may be thrown from without the casing into position to block said latch movement, said casing having a key hole and a key to operate 75 said bolt and latch for moving them to unlocked positions.

4. A lock mechanism to restrain a prisoner's limb movements, including a lock casing, a bolt slidable on the bottom of said casing, a spring latch slidable in a straight 85 line against a side wall of said casing at an angle to the bolt, a small opening in the opposite side wall of the casing whereby the bolt may be thrown from without the casing into position to block said latch movement, 90 said casing having a key hole and a key to operate said bolt and latch for moving them to unlocked positions, said bolt and latch having key engageable parts to cause an unlocking movement of both when the key is 95 rotated in one direction.

5. A lock mechanism to restrain a prisoner's limb movements, including a lock casing, a bolt slidable on the bottom of said casing, a spring latch slidable in a straight 100 line against a side wall of said casing at an angle to the bolt, a small opening in the opposite side wall of the casing whereby the bolt may be thrown from without the casing into position to block said latch movement, 105 said casing having a key hole and a key to operate said bolt and latch for moving them to unlocked positions, and relatively rotatable locking arms one of which is provided with latch engageable teeth in rotatable line 110 with the top of said lock casing.

6. A prisoner's cuff comprising clasping means, a lock casing rigidly mounted adjacent one end thereof, a locking arm pivoted at the other end and provided with teeth at its free end on a peripheral arc in rotative line with the top of said lock casing, a straight latch mounted to move in a straight line into and out of engagement with said teeth, a spring for said latch, a key engageable lug on the side of said latch, a bolt having a part to underlie said latch when the latter engages said teeth, a key engageable shoulder on said bolt and means extending for access from without the casing to move said bolt to underlie the latch independently of the key hole access to the lock casing.

In testimony whereof I have affixed my signature.

ELMER E. NEAL.
